UNITED STATES PATENT OFFICE.

ROBERT E. BURNS, OF SAN FRANCISCO, CALIFORNIA.

FRUIT-DRIER.

SPECIFICATION forming part of Letters Patent No. 251,408, dated December 27, 1881.

Application filed August 25, 1881. (No model.)

To all whom it may concern:

Be it known that I, ROBERT E. BURNS, a citizen of the United States, residing at San Francisco, in the county of San Francisco and State of California, have invented certain new and useful Improvements in Fruit-Driers, of which the following is a specification.

The objects of my invention are, first, to provide a fruit drier so constructed that the operator can regulate the heat and adapt it to the different kinds of fruits and vegetables to be treated, and to produce a uniformity of temperature throughout all of the drying-chambers while the heat is fully utilized; second, to provide a means whereby the heat can be shut off from one or all of the drying-compartments and little or much fruit be treated in the same machine. I accomplish these objects by the device illustrated in the accompanying drawings, in which—

Figure 1 is a front elevation partly broken away. Fig. 2 is a plan view, showing partitions beneath drying-compartment. Fig. 3 is a plan view, showing hot-air openings and their coverings or valves. Fig. 4 is a transverse section, showing deflectors and lower drying-tray. Fig. 5 is a plan view of one of the drying-trays. Fig. 6 is a sectional view on line X X of Fig. 5. Fig. 7 is a front end view of a drying-tray. Fig. 8 is a section taken on line Y Y of Fig. 5. Fig. 9 is a vertical transverse section of my improved dry-house.

Similar letters refer to similar parts throughout the several views.

35 A is a rectangular furnace, in one end of which is placed a brick fire-arch, B, open at the rear end, and having the usual door and draft-openings in front. Along the sides and ends of the walls of the drier I make openings C C for the admission of cold air upon all sides of the combustion and hot-air chambers, to be hereinafter more fully described.

40 The combustion-chamber D consists of a rectangular box of iron, (sheet-iron is preferable,) which fits within the walls of the furnace-chamber over the brick fire-arch in such a manner that a space of about six inches is left between the outer walls thereof and the inner walls of the furnace for the admission of cold air.

45 50 A horizontal partition, D', divides the combustion-chamber flatwise or longitudinally, and

in the upper part of the chamber are placed vertical partitions, so as to form flues E' E² E³, which communicate with each other at opposite ends of the chamber; and in one corner of the partition D' is made an opening, which connects the hot-air chamber with the flues. The front end of this flue-chamber is provided with the necessary man-holes and a chimney-flue, F.

Around the top of the furnace-walls a ledge 60 is formed to support a deflecting-plate, G, which is placed directly over the combustion-chamber, and forms a hot-air chamber, G', beneath, for storing up the hot air or caloric for use. Through this plate are made openings 65 H at intervals of space, or so as to open directly into the drying-compartments above, to be hereinafter more fully described. The openings are provided with sliding plates or doors H', which admit of the hot air being conducted to any one or all of the drying-chambers. In place of these openings, slots may be made in the deflecting plate at the sides of the lower drying-tray, so as to admit air from the hot-air chamber and deflect it from right to left 75 over the drying-trays by the air impinging against the cleats at the sides of the drying-chamber in its passage upward. These slots may be provided with slides in the same manner as the openings H. The top of this plate G 80 is laid with cement or mortar, or other non-conducting material, so as to control and prevent radiation or loss of heat, except through the proper openings, on withdrawal of the slides, and the top of these sliding plates or doors 85 may be covered with sand when closed, as a further check to the radiation of heat.

Immediately above the hot-air chamber are placed the drying-compartments, which are constructed of wood, and may rest upon a ledge 90 made around the outer edge of the wall of the furnace, and be provided with doors hinged at their upper or lower ends, so as to open outwardly.

To the vertical partitions which divide the 95 drying-chambers I I are connected cleats I' I², upon which the drying screens or frames are placed. The cleats shown at I' are closely joined to the face of the partition-wall, and those marked by the letter I² have a space of 100 about three inches left between them and the wall in an alternate manner, as shown, so that

the hot air will be deflected from right to left when the drying-trays and deflectors are in position, to be hereinafter more fully described.

Within each drying-compartment, and resting upon the top of the deflecting-plate G, I place the peculiarly-constructed deflectors J J', which consist of two plates, one of metal and one of wood, resting on feet, and placed one above the other, as shown. In the space K formed by the union of these plates a packing of sand, cement, or mortar is made, and over the top of the metal plate the wooden deflector J' is placed.

The edges of the metal plate may be turned up, so as to form a pan or dish to receive and hold the materials used as a packing.

The wooden plate may be connected to the bottom of the first or lower drying-tray; or the bottom of this tray may be made of wood, so as to break the force of the heat. By this means the initial or first volume of heat from the hot-air chamber is deflected, and does not strike the drying-trays above in a direct manner, but is controlled and diffused more generally, so as to gradually impinge upon the trays above.

When the sliding plates or doors are kept closed the deflecting-plates J may be dispensed with, and the rear end of the first drying-tray may be placed against the rear wall, leaving a space of six inches in front, and the heated air may be admitted through a slot made in the front edge of the deflecting-plate G, in which case the heated air will not strike the first tray, but will impinge upon the second tray, which is provided with a wooden bottom.

The drying-trays L, I make with double drying-screens L', which are kept separated by rabbits made along the frame.

The top edge of the front of the screen frame is cut away, as shown, for removing and replacing the upper screen without disturbing the lower screen or suffering a loss of heat.

The drying-compartments are provided with hinged doors, which cover the front of each tray when closed. The drying-trays are so placed in the drying-compartments as to deflect the heat from the furnace as it ascends upward in an alternate manner from front to rear—that is to say, the front of one drying-frame is placed so as to be flush with the door or front of the compartment and leave a space in the rear, between it and the rear wall of the chamber, by means of stops a a upon every alternate series of cleats, while the succeeding frame abuts against the rear wall of the chamber and provides a space in front of it, so that the hot air in ascending will be deflected from front to rear of the drying-compartment in its upward passage.

An air-tight finishing-chamber, N', is formed in the upper part of the compartment by means of sheet-iron partitions N N, the horizontal

partition forming the floor of said chamber, and the rear vertical partition being so arranged as to form one side of a flue, O, for the escape of moisture or an overcharge of heated air. In this upper or finishing chamber I am able, by interchanging the drying-trays, to finish drying any of the trays from beneath without moisture from the drying products below.

In order to more fully utilize the heated air, the flue or escape-pipe O is closed, and the heated air, laden with moisture from the trays below, is directed through openings R in the rear wall into a containing chamber or flue, R', formed of a sheet-iron roof and a wooden bottom.

Above the iron roof or cover a drying-chamber, S, is formed, in which products that have been partially dried are placed for the purpose of finishing or completing the drying process. By this construction of an auxiliary chamber having an iron bottom the moisture is not permitted to enter the chamber S, but is carried out by conducting pipes or flues through the rear walls or roof, and the heated air passes up through the iron roof into the chamber in a dry state.

My drying-compartments, when constructed of brick or masonry instead of wood and provided with trays of iron, will form an excellent oven for bakers.

Having thus described my invention, what I claim, and desire to secure by Letters Patent, is—

1. In a fruit-drier, the combination of the combustion-chamber D, consisting of an oblong metal box having horizontal flues E' E² E³, communicating at alternate ends, furnace-chamber G', plates G, having openings H and sliding doors H', and deflecting-plates J J', provided with feet, and placed one above the other upon the plate G, substantially as shown and described.

2. The combination, with the combustion-chamber D, deflecting-plates G J J', and chamber I I, separated by horizontal screens, of the air-tight finishing-chamber N' and flue O, substantially as shown and described.

3. In a drier provided with suitable flues, the auxiliary drying chamber or compartment S, located in the upper part of the drier and provided with a sheet-metal floor, whereby the heated air, laden with moisture, as it passes up, may be conducted through said flues and under the auxiliary chamber, and thus utilized, substantially as set forth.

In testimony that I claim the foregoing I have hereunto set my hand and seal this 6th day of August, 1881.

ROBERT E. BURNS. [L. S.]
